UNITED STATES PATENT OFFICE

OTIS J. STRAUGHAN, OF BROOKLYN, NEW YORK, ASSIGNOR TO MERGENTHALER LINOTYPE COMPANY, A CORPORATION OF NEW YORK

TYPOGRAPHICAL COMPOSING MACHINE

Application filed May 9, 1930. Serial No. 450,908.

This invention relates to typographical composing machines, such as linotype machines of the general organization represented in Letters Patent to O. Mergenthaler, No. 436,532, wherein circulating matrices and spacers are released from separate magazines by the manipulation of a keyboard and then composed in line, the composed line transferred to the face of a mold, the mold filled with molten metal to form a slug or linotype against the matrices which produce the type characters thereon, and the matrices and spacers thereafter elevated and returned by suitable mechanisms to the magazines from which they started.

The release of the matrices is effected by a series of finger keys (usually ninety in number) bearing the different characters of the corresponding matrices, whereas the release of the spacers (which are all alike) is effected by a single blank finger key. In the commercial machines, the keyboard is ordinarily provided with a locking device adapted when the machine is idle to prevent accidental depression of the finger keys and the consequent release of the matrices when the machine is subsequently started. Such a locking device is shown in the Kennedy Patent No. 1,397,971 and consists of a slotted plate slidably mounted upon the regular inclined front plate of the keyboard and which is adjustable at will to and from its active or locking position beneath the forward ends of the finger keys. This locking plate, however, functions only to lock the matrix releasing keys, the spacer releasing key being unaffected thereby and hence capable of manipulation at all times. As a result, it has been found in practice that occasionally some tool or other object, which has been carelessly placed upon or near the keyboard, will hold the spacer key depressed and cause the power mechanism controlled thereby to release many, if not all, of the spacers from the storage magazine and clog the assembling mechanism.

The present invention is intended to overcome these and other objections and contemplate, specifically, the provision of locking means for the spacer releasing key which are

operated automatically by the locking plate when the latter is adjusted to lock or unlock the matrix keys. In the preferred embodiment illustrated, such means include a fore-and-aft locking rod, which is adapted to be moved endwise by the adjustable locking plate into and out of engagement with a pin projecting laterally from one arm of the spacer key lever.

In the accompanying drawings, the invention has been shown merely in preferred form and by way of example and as applied to a machine of the class stated, but obviously many changes and alterations may be made therein and in its mode of application, which will still be comprised within its spirit. It should therefore be understood that the invention is not limited to any specific form or embodiment except insofar as such limitations are specified in the claims.

Referring to the drawings:

Fig. 1 is a front elevation of a portion of a linotype machine with the present improvements applied thereto;

Fig. 2 is a side elevation of the keyboard, partly broken away, showing the improved locking device for the spacer key in its inactive position;

Fig. 3 is a view similar to Fig. 2, showing the locking device for the spacer key in its active position; and

Fig. 4 is a plan view of the keyboard as shown in Fig. 3, with some of the parts broken away and omitted.

The matrices X and spacers Y (see Fig. 1) are stored in the respective magazines X¹, Y¹, and are released therefrom for composition in line by the regular power operated devices, which constitute part of the keyboard mechanism. These devices include a series of upright reeds A, a corresponding series of vertical actuating slides A¹ (Figs. 3 and 4), and intermediate cam yokes A², the latter being arranged in two banks on opposite sides of the reeds and sustained by means of trip dogs A³, connected to the slides, in engaging relation to a pair of underlying constantly driven rubber rolls A⁴. The arrangement is such that as the slides are raised, the cams are allowed to drop into peripheral contact with

the rolls and by their consequent rotation lift the yokes, which, in turn, operate the reeds. All of the slides A^1 , except one which is designated A^5 , are connected to the rear ends of the matrix releasing finger keys or key levers B , which are disposed in rows or tiers at different levels, and pivotally mounted for vertical movement on transverse rods C^1 in the keyboard C . The keyboard comprises as usual, the supporting frame C^2 , the two side plates C^3 , C^4 , the inclined front plate C^5 , and the rear plate C^6 . The front and rear plates C^5 and C^6 are formed with elongated slots c , c^1 , respectively, wherein the opposite ends of the finger keys are guided (see Fig. 4), and the length of these slots is such as to permit the required actuating movement of the finger keys.

The excepted actuating slide A^5 , (the one at the extreme right of the series) is connected to an arm D keyed or otherwise secured to a horizontal rock shaft D^1 , which extends completely across the keyboard and is journaled in the side plates C^3 , C^4 , thereof. The arm D is located at one end of the shaft D^1 adjacent the inner wall of the right side plate C^4 , and at its other end, the shaft is provided with a corresponding arm or finger piece D^2 , located adjacent the outer wall of the left side plate C^3 . In the arrangement shown, therefore, the arm D , rock shaft D^1 , and finger piece D^2 together constitute the spacer releasing key, which however may also include (as is usually the case) a second finger piece attached to the shaft D at the right of the keyboard C , or even a third finger piece at the top of the keyboard in the nature of a universal bar extending entirely across the keyboard (as is also frequently the case).

At this point, it may be stated that while the weight of the respective slides A^1 is sufficient to insure the return movement of the matrix keys B after depression, the weight of the actuating arm D^2 of the spacer key is considerably greater than the combined weight of the arm D and the associated slide A^5 , and for this reason it is customary to employ a counterbalancing spring to insure the return of the parts after the spacer key has been depressed, the said spring D^3 , as shown in Figs. 2 and 3, being anchored to the outer wall of the keyboard plate C^4 and connected to a pin D^4 , which projects laterally from the arm D through an enlarged aperture d formed in said plate.

When the spacer key is actuated, the slide A^5 is raised by the arm D , and the reed A^6 directly above the slide is operated in the usual way by the underlying cam yoke A^2 . This particular reed A^6 , as may be observed (Fig. 1), is considerably shorter than the other reeds and is connected at its upper end by a horizontal lever D^5 to the escapement of the magazine Y^1 , which controls the release of the spacers Y .

As before stated, the keyboard C is equipped with a locking plate E which (as best shown in Figs. 2, 3, and 4) is slidably mounted for manual adjustment back and forth upon the fixed front plate C^5 . The plate E (see Fig. 4) is practically a duplicate of the plate C^5 , being formed with corresponding elongated slots e through which the front ends of the matrix releasing finger keys B extend. In the forward position of the plate E , the slots e thereof are adapted to coincide with the slots c of the fixed plate C^5 , so that the finger keys will be free for actuation as usual; but when the locking plate E is in its rearward or active position, the lower end walls of its slots engage the bottom edges of the finger keys and thus lock the latter against depression or actuation.

The adjustment of the locking plate E is effected by means of a rotary cam plate F , pivoted by a pin f to the fixed front plate C^5 near the front edge thereof and arranged to engage the adjacent edge of the locking plate E . As will be apparent from the drawings, when turned anti-clockwise about the pivot pin f , the cam F pushes the locking plate E rearwardly to its active position (as shown by the full lines in Fig. 4) and when turned clockwise, it allows the locking plate to slide forwardly by gravity to its inactive position (as indicated by the dotted lines in said figure). To facilitate its turning, the cam plate F is provided with a depending grip or handle F^1 , which also serves as a stop to limit its movement in both directions.

According to the present invention, means are provided for automatically locking and releasing the spacer releasing key when the locking plate E is shifted to and from its active or locking position, respectively. In the embodiment illustrated, such locking means (as best shown in Figs. 2 and 4) consists of a fore-and-aft locking rod G arranged alongside the right-hand plate C^4 of the keyboard and attached thereto for endwise movement by a pin and slot connection G^1 . The front end of the rod G is pivotally connected by an angular bracket piece G^2 to the locking plate E , while its rear end is located in engaging relation to the pin D^4 of the arm D . The arrangement of the parts is such that when the locking plate E occupies its normal or inactive position (shown in Fig. 2) with its slots e in registry with those of the fixed front plate of the keyboard to permit the actuation of the matrix finger keys B , the rear end of the rod G will stand clear of the pin D^4 so as also to permit the actuation of the spacer finger key; whereas, when the plate E is shifted rearwardly to its active position (shown in Fig. 3) to carry the lower end walls of its slots e into engagement with the matrix keys B to prevent their actuation, the rod G will also be moved rearwardly into engagement with the pin D^4 so

as also to prevent the actuation of the spacer key. The spacer releasing mechanism as well as the matrix releasing mechanism may thus be locked and unlocked at will by the operation of the cam F.

While the invention has been herein shown and described in connection with a well-known keyboard lock, it nevertheless, when considered in its broader aspects, contemplates locking means for preventing the operation of the spacer releasing devices, when combined with any locking means arranged to be engaged directly with the finger keys in preventing the operation of the matrix releasing devices. Moreover, the construction and arrangement of the spacer key locking means as illustrated herein might itself be varied or modified; for example, a lug projecting from the rear edge of the locking plate E and arranged to cooperate with a pin projecting radially from the rock shaft D¹ or directly with the actuating arm D² could be substituted for the locking rod G and would function equally as well. These and other alterations or changes will readily suggest themselves to those skilled in the art and still be comprised within the scope of the invention as set forth in the following claims.

Having thus described my invention, what I claim is:

1. A keyboard mechanism for typographical composing machines including, in combination, matrix releasing mechanism, spacer releasing mechanism, separate and independently mounted locking devices for the two said mechanisms, and operative connections between said locking devices whereby the locking of one of the releasing mechanisms automatically effects the locking of the other.

2. In a keyboard mechanism for typographical composing machines, the combination with a supporting frame, a series of finger keys movably mounted therein for effecting the release of matrices, and a separate finger key also mounted in the said frame for effecting the release of spacers, of a locking device adjustable to active and inactive position into and out of direct engagement with the matrix releasing finger keys to prevent or permit their actuation, and a separate adjustable locking device for preventing or permitting the actuation of the spacer releasing key.

3. A combination as set forth in claim 2, characterized by the fact that the adjustable locking device therein recited for the matrix releasing keys is operatively connected to the locking device for the spacer releasing key so that the adjustment of one of said devices automatically effects the corresponding adjustment of the other.

4. In a keyboard mechanism for typographical composing machines, the combination with a supporting frame, a series of finger

keys movably mounted therein for effecting the release of matrices, and a separate finger key also mounted in the supporting frame for effecting the release of the spacers, of a locking device adjustable into and out of direct engagement with the spacer releasing key to prevent or permit its actuation.

5. In a keyboard mechanism for typographical composing machines, the combination with a supporting frame, a series of finger keys movably mounted therein for effecting the release of matrices, and a separate finger key also mounted in the said frame for effecting the release of spacers, of adjustable means for simultaneously locking or unlocking the matrix releasing keys and the spacer releasing key by direct engagement therewith.

6. In a keyboard mechanism for typographical composing machines, the combination with a series of power actuated devices, a corresponding series of vertical controlling slides associated therewith, and a series of pivoted matrix releasing finger keys and a pivoted spacer releasing key connected to the vertical slides, of a locking device adjustable into and out of direct engagement with the matrix releasing keys to prevent or permit the actuation of the connected power-device controlling-slides, and means controlled by said locking device to prevent or permit the actuation of the spacer releasing key and its connected power-device controlling-slide.

7. In a keyboard mechanism for typographical composing machines, the combination with a series of power actuated devices, a corresponding series of actuating slides associated therewith, and a series of matrix releasing finger keys and a spacer releasing finger key connected to the various actuating slides, of a locking device adjustable into and out of direct engagement with the matrix finger keys to prevent or permit the actuation of the connected slides, a locking device adjustable to prevent or permit the actuation of the spacer key and its connected slide, and a common operating device for effecting the adjustments of both of said locking devices simultaneously.

8. In a keyboard mechanism for typographical composing machines, the combination with a supporting frame, a series of finger keys movably mounted therein for effecting the release of matrices, and a separate finger key also mounted in the said frame for effecting the release of spacers, of a locking device adjustable into or out of direct engagement with the matrix releasing keys to prevent or permit their actuation, a fore-and-aft locking rod mounted at one side of the supporting frame and adjustable longitudinally into and out of engagement with the spacer releasing key, and connections between the two said locking devices whereby both

are adjusted to locking or unlocking position simultaneously.

5 9. A combination as specified in claim 8, characterized by the fact that the locking rod therein recited is slidably connected to the keyboard frame and has its rear end arranged to engage a pin projecting laterally from a part of the spacer releasing finger key.

10 10. A keyboard for typographical composing machines including, in combination, a supporting frame, a series of matrix releasing finger keys and a spacer releasing finger key pivotally mounted therein, a locking plate 15 slidably mounted on the supporting frame and formed with elongated slots through which the matrix releasing finger keys extend, said plate being adjustable to shift the end walls of its slots into or out of engagement with the associated finger keys so as to prevent or permit their actuation, and means connected to the adjustable locking plate and operated thereby to prevent or permit the actuation of the spacer releasing key.

20 25. In testimony whereof, this specification has been duly signed.

OTIS J. STRAUGHAN.
